UNITED STATES PATENT OFFICE.

EINER M. NELSON, OF PROVIDENCE, RHODE ISLAND.

RADIATOR CAP.

Application filed April 12, 1922. Serial No. 551,857.

To all whom it may concern:

Be it known that I, EINER M. NELSON, a citizen of the United States, residing at Providence, in the county of Providence and State of Rhode Island, have invented certain new and useful Improvements in Radiator Caps, of which the following is a specification.

This invention relates to a closure device 10 for receptacles, the same being more particularly adapted for use as a closure cap for the filling-opening in automobile radiators, and the object of this invention is to provide simple and effective means where- 15 by the closure cap may be readily applied and removed without being obliged to screw the same into and out of the threaded neck of the filling-opening.

With these and other objects in view, the 20 invention consists of certain novel features of construction, as will be more fully described, and particularly pointed out in the appended claims.

In the accompanying drawings: 25 Figure 1 is a front elevation showing a portion of a radiator with my improved closure-cap applied to the filling-opening therein.

Figure 2 is a sectional elevation showing 30 the bushing member as permanently screwed into the filling-neck and the cap as releasably connected to the bushing member by engagement of a set of pins with the corresponding set of inclined or cam-shaped 35 slots.

Figure 3 is a sectional elevation of the 40 cap, showing the inwardly-projecting pins on the same.

Figure 4 is a view of the under side of the 45 cap, showing the arrangement of the inwardly-extending locking pins.

Figure 5 is a side elevation of the bushing member showing a portion as being threaded and another portion as being provided 45 with a set of inclined slots.

Figure 6 is a top view of the bushing-member showing the relative positions of the different slots.

Figure 7 is a perspective view of the ten- 50 sion-plate which is located in the head-member and pressed downwardly to apply the tension to the cap.

It is found in practice very desirable to provide means whereby a radiator cap may

be readily applied to and removed from the 55 filling-opening without the necessity of screwing the same into and out of the opening, which operation often requires considerable time and careful manipulation owing to the fact that the threads so often become crossed after which the cap is very liable to be lost, but by my improved construction it is only necessary that the cap shall be positioned and turned but a portion of a revolution when it is firmly and automatically locked in position and the same may be readily removed when desired, and the following is a detailed description of one construction by which these results may be accomplished:—

With reference to the drawings, 10 designates an automobile radiator which is provided with the usual filling neck 11 threaded on its inner surface as at 12 for the reception of the old style cap and to take the 75 place of this old style cap, I have provided a bushing member 13 which is threaded for a portion of its length as at 14 to be screwed and permanently fixed into the threaded portion of the radiator neck, the upper portion of this bushing being provided with a plurality of grooves 15 in its face set around at intervals, three being indicated in the drawings.

These grooves are arranged to lead from 85 the upper edge of the bushing downwardly on an angle and their inner ends are preferably turned upwardly as at 16 providing retaining notches into which the locking pins 17 of the cap 18 are drawn by means 90 presently described.

The pins 17 in this cap 18 are preferably located as illustrated in Figure 4, to register with corresponding slots 15 in the bushing so that when the cap is positioned on the outer edge of the bushing the pins will fit in said slots and by a turn of the cap relative to the bushing a portion of a revolution, these pins will follow down the inclined slots into the notches 16 at their inner ends.

In order to draw these pins into these upturned notches of the slots to lock the cap against being accidentally turned backward, 105 I have formed an inwardly-extending shoulder 19 on the inner face of the cap, and I have provided a thin plate 20 which may be of metal, rubber or other suitable ma-

terial, as at 21 to pass the pins 17 and adapted to be bent and sprung into the recessed portion 22 of the cap beyond the shoulder 19 so that when expanded again 5 this plate will engage the shoulder 19 and be prevented by it from dropping out.

Before positioning this plate in the cap, I first set a spring 23 preferably spirally wound into the head with its upper coil about 10 the locating pin 24, which spring engages the plate when positioned therein to force it downwardly, whereby when the cap is turned into locked position on its bushing, this plate will be raised from its shoulder 19 to 15 rest against the upper edge of the bushing as shown in Figure 2, and the tension of the spring then working between the plate and the top of the cap, serves to lift its pins 17 into the upturned ends 16 in the bushing.

20 By this construction it will be seen that the cap is thus releasably secured against being accidentally removed from the bushing without first pressing downwardly on the cap and then turning it backward a small portion 25 of a revolution and in applying the cap it is only necessary to turn it in the opposite direction a small portion of a revolution until its pins bring up against the inner ends of their slots at which time the spring 30 will automatically snap these pins into the notches to secure the cap in position.

The device is extremely simple and practical in its operation and by its use the screwing of the cap into the neck of a radiator is 35 obviated.

The foregoing description is directed solely towards the construction illustrated, but I desire it to be understood that I reserve the privilege of resorting to all the mechanical 40 changes to which the device is susceptible,

the invention being defined and limited only by the terms of the appended claims.

I claim:

1. A closure device for receptacles, comprising a short tubular bushing member 45 threaded for a portion of its length to be screwed into the filling opening and also provided with grooves in its face leading from its upper edge downwardly on an angle and notched at their inner ends, and a cap-member fitting over said bushing and having pins set to enter said grooves by a relative rotation of the cap, a thin disk plate in said cap to engage the upper edge of the tube, and a spring acting between said plate and cap to 50 lift said cap to cause its pins to enter said notches to releasably lock said cap in position.

2. A closure device for receptacles, comprising a short tubular bushing member 60 threaded for a portion of its length to be screwed into the filling-opening, and also provided with grooves in its face leading from its upper edge downwardly on an angle and notched at their inner ends, and a cap-member fitting over said bushing and having an inwardly-extending shoulder, a thin disk plate retained by said shoulder when the cap is removed, and a spring acting 65 between said plate and cap to press the plate into engagement with said shoulder, said cap also having a set of inwardly-extending pins to fit into said grooves in the bushing and follow downwardly therein by a relative rotation of said cap, said plate then engaging the edge of said bushing to lift the cap-pins into their notches and releasably 70 retain the cap in position.

In testimony whereof I affix my signature.
EINER M. NELSON.
